UNITED STATES PATENT OFFICE.

JOHN T. GREENWOOD, OF KALAMAZOO, MICHIGAN.

IMPROVEMENT IN AIR-HEATERS.

Specification forming part of Letters Patent No. 222,395, dated December 9, 1879; application filed September 30, 1879.

To all whom it may concern:

Be it known that I, JOHN T. GREENWOOD, of Kalamazoo, county of Kalamazoo, State of Michigan, have invented new and useful Improvements in Air-Heaters, of which the following is a specification.

My invention has for its object the construction of a device, by the use of which fresh cold air is conveyed into a dwelling, public building, or railroad-car in a heated condition. Another object is to prevent the combustion of soot in chimneys and pipes.

The prominent features of the utility of such a device are—

First, economy. By practical experiments with my device I find a saving of at least one-half the fuel is effected over the ordinary consumption without its use.

Second, health. By its use the people breathe pure warm air, obviating the inhalation of noxious poison and cold drafts.

Third, safety. By the use of my heater conflagrations are prevented.

In the accompanying drawings, forming a part of this specification, Figure 1 is a perspective of the device as adjusted to a stove; Fig. 2, a longitudinal section; Fig. 3, perspective of device, showing top end; and Fig. 4, surface view of top.

The heater consists in a cylindrical drum, B, in which is located pipe or tubes A and c c.

In the device I have constructed, tube A extends obliquely through the drum B. (Seen in Fig. 2.) To the top of said tube is attached an elbow, A', for the purpose of delivering the heated air out into the room, as the hot draft of air without its use would ascend directly to the upper ceiling. To the lower end of said tube A is connected pipe C, having a funnel-shaped orifice, f, for the purpose of receiving the air in the room near the floor, when the device is used for warming a room without the introduction of cold air from outside. To pipe C is connected pipe e e, (illustrated in Fig. 1,) which extends down through the floor and out through the sill.

When thus arranged, cold air is transmitted through pipes e e, C, and tube A, in the

latter of which it is heated and delivered out in the room through elbow A'. Tubes c c are located vertically within the drum B. The important use of these tubes is, that pipes may be connected with them extending to rooms in an upper story, whereby one stove is made to do the service of many.

D is a perforated cylinder, over top of which pipe L is attached, said cylinder being inclosed at the bottom, and having a plate, F, hung or stationed a little below it, which plate may be much larger, if deemed practicable, and notched or perforated, to surround the tubes. I call this feature of my invention a "flame and spark arrester," as it retards them from entering the stove-pipe, while the smoke readily passes through the perforations; also, by the flame being arrested at this point it is thrown back around the tubes and surface of the drum, whereby greater heat is obtained.

In manufacturing the device, the heads of the drum may be cast with raised rims or shoulders surrounding the perforations through them, to which can be attached the tubes A and c c. An illustration of said rims is shown at D', which rim connects with pipe h and K, which set over the hole in stove S intended for pipe.

It will be seen by the construction of my device that the flames come directly in contact with tubes A and c c, which is deemed a great improvement over the common double-cylinder drum.

To illustrate, pipe A may be located exactly perpendicular, or otherwise, and may be bulged, bent, or elbowed in the center, as also may pipe c c be located as shown, or extend obliquely or horizontally through the drum B, and may consist of any number and form, so long as my purpose is effected, by means of pipes passing through a drum, substantially as shown and described, whether said drum and tubes be provided with flame-arrester F D, elbow A', and pipe C, or whether other accessories equivalent be substituted.

What I claim as new is—

1. Drum B, with tubes A and c c, elbow A', perforated cylinder D, plate F, and pipe C, combined, adapted, and arranged for use

substantially as shown and specified, for the purpose set forth.

2. The combination of the drum B, provided with tubes A and c c, and flame-arrester F D, with a stove and pipe, and pipe e e, constructed and arranged substantially as specified and shown, for the purpose set forth.

3. Flame and spark arrester consisting of

perforated cylinder D and deflecting-plate F, in combination with drum B, substantially as shown and specified, for the purpose set forth.

J. T. GREENWOOD.
